UNITED STATES PATENT OFFICE.

JOHN G. ROBINSON AND LEO J. SCHLITZER, OF ELDORADO, KANSAS.

PORTABLE FIRE EXTINGUISHER.

Application filed January 7, 1922. Serial No. 527,634.

To all whom it may concern:

Be it known that we, JOHN G. ROBINSON and LEO J. SCHLITZER, citizens of the United States, residing at Eldorado, in the county 5 of Butler and State of Kansas, have invented certain new and useful Improvements in Portable Fire Extinguishers; and we do declare the following to be a full, clear, and exact description of the invention, such as 10 will enable others skilled in the art to which it appertains to make and use the same, reference being had to the accompanying drawings, and to the figures of reference marked thereon, which form a part of this specification. 15

This invention relates to portable fire extinguishers, and the primary object of the invention is to provide a novel and efficient construction of fire extinguishers in which a 20 liquid is adapted to be discharged by pressure generated within the container, the chemicals for generating the pressure being normally separated and adapted to combine at the will of the operator.

The purpose of maintaining the chemicals separated is that the extinguisher can be charged in a manner to be ready for use at any time, but whereby the chemicals will not deteriorate as they are liable to do if they 25 are combined before being introduced into the container.

The novel features of the invention will be described hereinafter, reference being had to the accompanying drawings, in 30 which—

Fig. 1 is a view partly in elevation and partly in section of a fire extinguisher constructed in accordance with our invention, the parts being shown for separating the 35 chemicals, and

Fig. 2 is a similar view showing the chemicals combined, whereby pressure may be provided for forcing out the liquid.

In carrying out our invention, we prefer 40 to employ a cylindrical container 1, closed at one end by a permanent closure 2, and at the other by a removable cap 3. The removable cap 3 is threaded at 4 to the upper end of the cylinder 1, and it has a central 45 opening 5, surrounded by a depending cup comprising a rim 6, with an inwardly projecting flange 7, the rim having openings 8, as will be clearly seen by reference to the drawings. The upper portion of the cup-shaped member is threaded as at 9 to receive a threaded plug 10, having a depend-

ing rim or ring 11 provided with openings 12 adapted to align with the openings 8 in the rim 6. The cup-shaped member constitutes a supporting bracket to retain chemical containers, one of which is larger than the other and one of which constitutes a stopper for the other, the contents of the two being normally separated, but adapted to be combined by appropriate mechanism 65 which will be hereinafter described.

The flask or container 13 is shown as consisting of a substantially elongated cylindrical member closed at the end 14 and having an outwardly projecting flange 70 15 at its upper end to lie upon the flange 7, by means of which the flask 13 is supported. The complementary flask 16 tightly fits within the flask 13 and serves as a stopper to close off the chamber 17, in which may 75 be located a suitable chemical, such as soda. The flask 16 preferably contains an acid, for example, sulfuric acid, and its lower end, or bottom is provided with a disruptible seal 18, which may be formed integral therewith 80 or provided in any suitable manner, so that it will be disrupted or broken upon the application of pressure, so that communication may be had between the chamber 17 and the chamber 19 within the flask 16, thus 85 permitting the two chambers to intercommunicate. The upper end of the flask 16 is threaded as at 19' to receive a threaded plug 20, having a stuffing box or gland 21, within which is slidably mounted a hollow plunger 90 rod 22, provided at its lower end with a plunger 23 adapted to break or disrupt the seal 18.

The hollow plunger rod is provided with 95 openings 24 and 25 normally out of communication with the interior of the cylinder 1, as will be apparent by reference to Fig. 1. The upper end of the plunger rod is closed off by a sealing cap 26. The plug 20 is provided with a peripheral, laterally projecting flange 27, which may rest upon a packing washer 28 lying upon the upper ends of the flasks 13 and 16, so that they will be sealed against communication with the interior of the cylinder 1, and when the rod 100 22 is in its uppermost position, the openings 24 will be sealed by the packing 27' and the openings 25 by the packing 27''. A suitable liquid 29 may be provided within the cylinder 1, but not quite fill the same, 105 and a discharge tube 30 may be carried by the cap 3, having its inlet 31 at the bottom 110

of the cylinder 1 and its outlet 32 outside the cap 3, as clearly shown in the drawings.

After the parts are assembled as shown in Fig. 1, it will be apparent that the chemicals will keep indefinitely because they will be separated and can not combine so that chemical actions and reactions can take place.

When it is desired to use the extinguisher, the rod 22 can be reciprocated, so that its plunger will break the seal 18, permitting the acid to combine with the soda so that gas will be formed. The gas can pass from the two chambers 17 and 19 through the openings 24, through the hollow portion of the rod 22, through the openings 25, openings 12 and 8, onto the body of the liquid and force it through the tube 30, to be discharged from the nozzle 32.

When it is desired to re-charge the extinguisher, the plug 10, whose flange 11 bears on the flange of the plug 20, may be removed, whereupon the plug 20 may be removed. The rod 22 may be grasped to lift the chemical containers off the seat formed by the cup-shaped member of the cap 3, and new chemical containers can be introduced in the form of renewals and liquid placed in the cylinder 1, the containers being put back in place when the device is ready for use.

It will be observed that when the device is operated so as to cause the chemicals to come out, that the entire contents of the extinguisher will be forced out so that it will be necessary to renew each time the device is operated. This is a very important feature of the invention, because this will insure that a full charge is ready each time the extinguisher is used, this being a material advantage over that class of extinguishers in which fractional quantities can be released, with the result oftentimes that when the extinguisher is most needed, there is only a small quantity remaining which will be available to apply to the fire.

It will be apparent from the foregoing that the device is efficient, inexpensive and easily operated and that the chemicals may be retained in their original condition without fear of deterioration and that the device is capable of being used whenever desired.

What we claim and desire to secure by Letters Patent is:

1. A fire extinguisher comprising a liquid container having a top opening, a depending cup suspended from the top and surrounding the opening, the cup consisting of a rim having openings and an inwardly turned flange at its lower edge, a plug threaded in the edge of the opening in the top of the container, two nested chemical containers, the inner one of which is shorter than the outer

one, the outer container having a top flange resting upon the flange of the cup, a plug supporting the inner container, the plug having a flange supported above the flange of the outer chemical container, the lower ends of the first plug bearing against the flange of the second plug to hold it and the chemical containers rigid with the cup, an open discharge pipe leading through the top of the liquid container, a hollow plunger guided in the two plugs and movable to break the bottom of the inner container, the hollow plunger having openings communicating with the containers and having openings communicating with a space between the first and second plugs so that gas can pass from the inner containers through the opening in the rim of the cup into the liquid container to apply pressure upon the liquid in the liquid container, and a discharge pipe leading from the liquid container to atmosphere.

2. A fire extinguisher comprising a liquid container having a depending, cup-shaped recess with a central opening in the bottom thereof to provide a rim flange, a cylindrical chemical container having a closed lower end and an open upper end, a flange on the container resting upon the rim flange of the cup-shaped recess, a second cylindrical container nested in the first chemical container, a plug closing the top of the second chemical container and having a flange co-extensive with the flange of the first chemical container, a packing between the flange of the plug and the flange of the first chemical container, a stuffing box in the plug, a hollow plunger longitudinally movable in the stuffing box, the plunger having openings adapted to be brought into communication with the second chemical container whereby communication can be established between the chemical containers and the hollow portion of the plunger, a plug closing the top of the cup-shaped recess in the liquid container and having a stuffing box through which the hollow plunger extends, there being a space between the first and second plugs, the hollow plunger having openings adapted to communicate with the space to establish communication between the hollow plug in said space, the walls of the second plug and the depending wall of the cup-shaped recess having aligning openings to establish communication between the space and the interior of the liquid container, and a discharge pipe communicating with the bottom of the liquid container.

In testimony whereof we affix our signatures.

JOHN G. ROBINSON.
LEO J. SCHLITZER.
